UNITED STATES PATENT OFFICE

158,197

MOTORCYCLE FRAME

**Fred A. Kimberley, Greet, Birmingham, England,
assignor to The James Cycle Company Limited,
Greet, Birmingham, England**

**Application April 28, 1948, Serial No. 146,014
In Great Britain January 10, 1948**

Term of patent 7 years

(Cl. D90—8)

To all whom it may concern:

Be it known that I, Fred Arthur Kimberley, a British subject, residing at Birmingham, in the county of Warwick, England, have invented a new, original, and ornamental Design for a Motorcycle Frame, of which the following is a specification, reference being had to the accompanying drawing, forming part thereof.

Figure 1 is a perspective view of a motorcycle frame embodying my new design.

Figure 2 is a plan view of the motorcycle frame depicted in Figure 1.

I claim:

The ornamental design for a motorcycle frame, as shown.

F. A. KIMBERLEY.
